HIGH-POWER OSCILLATOR TUBE

John E. Gorham, Spring Lake, N. J.

Application June 22, 1943, Serial No. 491,800

19 Claims. (Cl. 250—27.5)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to oscillators, and more particularly to self-contained oscillator tubes.

Electron tubes have already been made which are nearly self-contained oscillators, particularly for the generation of ultrahigh frequency power. Such tubes, however, have a number of disadvantages. The amount of power generated has been limited. Although tuned loops have been disposed within the tube envelope for tuning the anode-to-anode and grid-to-grid circuits, it has nevertheless been necessary to tune the cathode-to-cathode circuit by means of an external circuit, which has sometimes proved cumbersome and troublesome. In some tubes it has been necessary for a number of stems and lead-ins to project in the same direction from the tube envelope at points relatively close to one another, thus making the construction of the tube a difficult glass-blowing job.

The primary object of the present invention is to generally improve oscillator tubes, and more particularly ultra high frequency oscillator tubes having resonant loops within the tube envelope. A more specific object is to provide such a tube having greatly increased power output. Still another object is to facilitate tuning the cathode circuit by providing capacitance loading between the cathodes, thereby reducing the inductance needed for resonance. In fact, in accordance with a further feature and object of the invention, the necessary inductance may be provided by a reduced length of cathode lead-in housed within the tube envelope.

Still another object is to devise an oscillator tube in which nearly all of the lead-ins extend in different directions at widely spaced points on the tube envelope, thus simplifying the glass-blowing job incident to construction of the tube.

To accomplish the foregoing and other objects which will hereinafter appear, my invention resides in the oscillator tube elements, and their relation one to the other, as hereinafter are more particularly described in the specification and sought to be defined in the claims. The specification is accompanied by a drawing in which

Figure 1 is a horizontal section through an oscillator tube embodying features of my invention;

Figure 2 is a vertical section taken approximately in the plane of the line 2—2 of Figure 1;

Figure 3 is an end view of the tube;

2

Figure 4 is a detail showing the cathode;

Figure 5 is a detail showing the electrode assembly and cathode choke;

Figure 6 is a schematic diagram explanatory of the oscillator tube; and

Figure 7 is a detail similar to Figure 4, but showing a modification.

Referring to the drawing, and more particularly to Figure 6, the tube comprises a glass envelope 12 within which are disposed two electrode assemblies, each comprising a cathode 14, a grid 16, and an anode 18. As will later appear when considering the structure of the tube, the cathodes are preferably disposed in end-to-end relation on a common axis with the closed ends of the cathodes adjacent one another, thereby providing a capacitance 20 which facilitates tuning of the cathodes by reducing the length of cathode lead-in needed for resonance. This length is symbolically defined or terminated by the chokes 22. These are shown outside the tube envelope in Figure 6, and may be located in this manner, but as will later appear, they may also be housed within the tube envelope.

The anodes are connected to one another by a tuned loop 24, and the grids are connected by a tuned loop 26, thus joining the two electrode assemblies for push-pull operation. The loops 24 and 26 are located relatively close together, thereby providing regenerative coupling therebetween. In the actual structure, it is convenient to locate the loop 26 within the loop 24. While not essential, it is also convenient to make the structure symmetrical by the addition of equal, oppositely-extending loops 24' and 26'.

Referring now to Figure 1 of the drawing, it will be seen that the cathodes 14 are hollow sheet metal cans, heated by means of internally-carried heater filaments 30. The cans are preferably coated on the outside with a suitable electron emissive material, this being best shown at 32 in Figure 4. The cathode can is carried by a lead-in 34 which is preferably a hollow tubular extension of the cathode can. In such case, the filaments 30 may be supported and energized by means of coaxial conductors 36 extending through the lead-ins 34. It will be observed in Figures 1 and 3 that the lead-ins 34 extend in opposite directions and project from opposite sides of the envelope.

The inner ends 38 of the cathodes are disposed near enough together to provide capacitance loading corresponding to the condenser 20 shown in Figure 6. In designing the tube, the desired capacitance value is determined by the spacing

and area of the ends 33, and, if desired, the ends may be tapered as shown, should it be necessary to reduce that area. The effective inductive length of the lead-in 34 is terminated or defined by the position of a suitable choke 40. The chokes 40 are most conveniently of the concentric type and approximately a quarter wave in length. It will be seen that the vacuum tube 12 is so shaped as to enclose the chokes 40, and more specifically, that the outwardly-projecting glass stems 42 are enlarged sufficiently to house the chokes.

In Figures 1 and 4, the entire cathode lead-in 34 is indicated to have the same diameter as the cathode can. However, for high power purposes a considerable cathode area may be needed for adequate electron emission. It may therefore be pointed out that it is not essential to have the entire cathode lead-in diameter as great as that of the cathode, although it is desirable to maintain the cathode diameter for the resonant length. This is illustrated in Figure 7, in which the cathode can 44 extends at full diameter to the point of connection of the concentric choke 46. The remainder of the cathode lead-in may be substantially smaller in diameter, as is indicated at 48. The glass stem 50 is sealed to the reduced lead-in 48. In this way, the diameter of the cathode may be increased to very large size, say up to 1" or 1½", while making the lead-in 48 out of Kovar or other tubing having a diameter of, say, only ¾". The center wire 52 is coaxial of the lead-in 48 and cathode 44, and supplies heating current for the filament, all as previously described.

The grids 16 are cylindrical cages of wires and are disposed concentrically about the cathodes 14. The adjacent ends of the grids are secured to the grid-to-grid loops 26 and 26'. They are formed of appropriate heavy gauge metal, as here shown, or if desired may be made of lighter weight sheet metal, but in that case are preferably flanged slightly at the edges in order to stiffen the same.

The anodes 18 are cylindrical and are disposed concentrically about the cathodes 14 and grids 16. The adjacent ends of the anodes are welded or otherwise secured to anode loops 24 and 24'. Here again the metal may be heavy gauge metal as illustrated, or may be lighter gauge metal suitably flanged at the edges to stiffen the loops. It will be seen from inspection of Figure 2 that the anode loops are preferably wide enough to receive the anodes, the sides of the loops being apertured to clear the space within the anodes for free passage of the grids 16. In similar fashion, the grid loops are preferably wide enough to receive the inner ends of the grids, the sides of the grid loops being apertured to clear the space within the grids for free passage of the cathodes. This relation is also shown in Figure 5, in which it will be seen that the cathode 14 projects through the grid loops 26, 26', and that grid 16 projects through the anode loops 24, 24'.

The anodes and anode loops are supported by a pair of lead-ins 54 (Figures 2 and 3), which project in a direction perpendicular to the plane of the loops and cathode lead-ins. With the tube in the position shown, the loops and cathode lead-ins extend horizontally, and the anode lead-ins 54 project upwardly. The attachment at the lower ends 54 may be made in any desired fashion, that here shown making use of ears 56 on the anode loops, said ears being received in slots cut in the lower ends of the lead-ins 54, the parts then being pinned or welded together. The lead-

ins 54 preferably pass through and are sealed to upwardly-directed glass stems 58.

It will be understood that the lead-ins 54 are connected to an appropriate transmission line, and that direct current anode potential may also be supplied by way of lead-ins 54.

The grids 16 are mounted on the grid loops 26, 26', and the latter in turn are supported by lead-ins 60, which pass downwardly through glass stems 62. In Figure 1 it will be seen that the grid loops 26, 26' may be provided with bent sheet metal ears 64, in which the upper ends of lead-ins 60 (Figures 2 and 3) are received. The grid lead-ins extend in a direction opposite the anode lead-ins. In general, nearly all of the lead-ins extend in different directions, and are located at widely spaced points on the tube envelope, thus facilitating the glass-blowing job needed to complete the tube. The grid lead-ins 60 are located at the ends or potential nodes of the grid loops, it being assumed that the lead-ins will not be used in any external circuit other than for grid bias supply.

It is believed that the construction and operation of my improved high power oscillator tube, as well as the advantages thereof, will be apparent from the foregoing detailed description. The cathode may be made large in diameter for adequate electron emitting surface, hence large power outputs may be obtained. Capacitance loading to facilitate tuning of the cathode lead-ins may be obtained from the cathode themselves; and the tuned length of lead-in, and even concentric chokes defining that length may be housed within the tube envelope. The connections to the electrodes are simple D.-C. or low frequency power connections for cathode heating, and for grid bias, the only lead-ins carrying ultrahigh frequency being the anode lead-ins. Inasmuch as all of the lead-ins extend in different directions, or are located at widely spaced points on the tube envelope, the necessary glass-blowing work may be performed with minimum difficulty.

It will be understood that while symmetrical or double loops have been shown for the grid-to-grid and anode-to-anode circuits, single loops may be employed. It will also be understood that the grid-to-grid and anode-to-anode loops need not be located one within the other, although that is the most convenient structural arrangement. It will also be understood that insofar as the invention is directed to a novel disposition of loops and lead-ins to facilitate construction and glass-blowing, the cathode need not be a hollow can with indirect heating, and instead may be an exposed filamentary-type cathode.

It will therefore be apparent that while I have shown and described my invention in a preferred form, many changes and modifications may be made in the structure disclosed without departing from the spirit of the invention as sought to be defined in the following claims. In some of the claims the loops and cathode lead-ins are described as projecting vertically upward, and the grid lead-ins as depending vertically downward, but it will be understood that these directions are relative, and that the tube may under special circumstances be turned to a position somewhat different from the normal position here shown without preventing successful operation of the tube.

I claim:

1. An ultrahigh frequency tube comprising an evacuated glass envelope carrying a pair of electron trode assemblies, each of said assemblies includ-

ing a generally cylindrical cathode can closed at its inner end, said end comprising a flat surface perpendicular to the longitudinal axis of said cathode, a cathode lead-in extending outwardly from said can, a grid surrounding said cathode, and an anode surrounding said grid, said electrode assemblies being disposed end-to-end on a common axis colinear with the axes of the cathodes, with the flat surfaces of the cathode assemblies adjacent one another whereby said surfaces form a radio-frequency condenser providing capacitance loading for facilitating tuning of the cathodes.

2. An ultrahigh frequency tube comprising a glass envelope carrying a pair of electrode assemblies, each of said assemblies including a cylindrical cathode can closed at its inner end, a cathode lead-in extending outwardly from said can, a grid surrounding said cathode, and an anode surrounding said grid, said electrode assemblies being disposed end-to-end on a common axis with the closed ends of the cathode assemblies adjacent one another providing cathode-to-cathode capacitance loading for facilitating tuning of the cathodes, the outwardly oppositely projecting lead-ins of the cathodes having radio-frequency chokes within said envelope at a point defining the inductance for providing resonance with the aforesaid cathode-to-cathode capacitance.

3. An ultrahigh frequency tube comprising an evacuated glass envelope carrying a pair of electrode assemblies, each of said assemblies including a cylindrical cathode can closed at its inner end, said end comprising a flat surface perpendicular to the longitudinal axis of said cathode, a heater filament in said can, a cathode lead-in extending outwardly from said can, a grid surrounding said cathode, and an anode surrounding said grid, said electrode assemblies being disposed end-to-end on a common axis colinear with the axes of the cathodes with the flat surfaces of the cathode assemblies adjacent one another whereby said surfaces form a radio-frequency condenser, providing cathode-to-cathode capacitance loading for facilitating tuning of the cathodes, the outwardly oppositely projecting lead-ins of the cathodes having concentric chokes thereon within said envelope defining the inductance for providing resonance with the aforesaid cathode-to-cathode capacitance.

4. An ultrahigh frequency oscillator tube comprising a glass envelope carrying a pair of electrode assemblies and resonant loops, each of said assemblies including a cylindrical cathode can closed at its inner end, said end comprising a flat surface perpendicular to the longitudinal axis of said cathode, a heater filament in said can, a cathode lead-in extending outwardly from said can, a grid surrounding said cathode, and an anode surrounding said grid, said electrode assemblies being disposed end-to-end on a common axis colinear with the axes of the cathodes with the flat surfaces of the cathode assemblies adjacent one another, whereby said surfaces form a radio-frequency condenser, one of the aforesaid loops being a grid-to-grid loop, and another loop being an anode-to-anode loop, said anode-to-anode loop enclosing the aforesaid grid-to-grid loop.

5. An ultrahigh frequency oscillator tube comprising a glass envelope carrying a pair of electrode assemblies and resonant loops, each of said assemblies including a generally cylindrical cathode can closed at its inner end, a heater filament in said can, a cathode lead-in extending out-

wardly from said can, a grid surrounding said cathode, and an anode surrounding said grid, said electrode assemblies being disposed end-to-end on a common axis with the closed ends of the cathode assemblies adjacent one another providing capacitance loading for facilitating tuning of the cathodes, one of the aforesaid loops being a grid-to-grid loop, another loop being an anode-to-anode loop, the outwardly oppositely projecting lead-ins of the cathodes having concentric chokes thereon at a suitable point defining proper inductance providing resonance with the aforesaid cathode-to-cathode capacitance.

15 6. An ultrahigh frequency oscillator tube comprising an evacuated glass envelope carrying a pair of electrode assemblies and resonant loops, each of said assemblies including a generally cylindrical cathode can closed at its inner end, a heater filament in said can, a cathode lead-in extending outwardly from said can, a grid surrounding said cathode, and an anode surrounding said grid, said electrode assemblies being disposed end-to-end on a common axis with the closed ends of the cathode assemblies adjacent one another providing capacitance loading for facilitating tuning of the cathodes, one of the aforesaid loops being a grid-to-grid loop, another loop being an anode-to-anode loop, said anode-to-anode loop enclosing the aforesaid grid-to-grid loop, the outwardly oppositely projecting lead-ins of the cathodes having concentric chokes thereon at a suitable point defining proper inductance providing resonance with the aforesaid cathode-to-cathode capacitance, the aforesaid glass envelope enclosing the aforesaid loops, chokes and the electrode assemblies.

20 7. An ultrahigh frequency oscillator tube comprising a glass envelope carrying a pair of electrode assemblies and four resonant loops, each of said assemblies including a generally cylindrical cathode can closed at its inner end, a heater filament in said can, a cathode lead-in extending outwardly from said can, a grid surrounding said cathode, and an anode surrounding said grid, said electrode assemblies being disposed end-to-end on a common axis with the closed ends of the cathode assemblies adjacent one another, two of the aforesaid loops being grid-to-grid loops extending in opposite direction, the other two loops being anode-to-anode loops extending in opposite direction, said anode-to-anode loops enclosing the aforesaid grid-to-grid loops.

25 8. An ultrahigh frequency oscillator tube comprising a glass envelope carrying a pair of electrode assemblies and four resonant loops, each of said assemblies including a generally cylindrical cathode can closed at its inner end, a heater filament in said can, a cathode lead-in extending outwardly from said can, a grid surrounding said cathode, and an anode surrounding said grid, said electrode assemblies being disposed end-to-end on a common axis with the closed ends of the cathode assemblies adjacent one another, said ends providing a cathode-to-cathode capacitance loading for facilitating tuning of the cathodes, two of the aforesaid loops being grid-to-grid loops extending in opposite direction, the other two loops being anode-to-anode loops extending in opposite direction, the outwardly oppositely projecting lead-ins of the cathodes having concentric chokes thereon at a suitable point defining proper inductance which forms a resonance circuit with the aforesaid cathode-to-cathode capacitance.

30 9. An ultrahigh frequency oscillator tube com-

prising an evacuated glass envelope carrying a pair of electrode assemblies and four resonant loops, each of said assemblies including a generally cylindrical cathode can closed at its inner end, a heater filament in said can, a cathode lead-in extending outwardly from said can, a grid surrounding said cathode, and an anode surrounding said grid, said electrode assemblies being disposed end-to-end on a common axis, with the closed ends of the cathode assemblies adjacent one another, said ends providing a cathode-to-cathode capacitance loading for facilitating tuning of the cathodes, two of the aforesaid loops being grid-to-grid loops extending in opposite direction and disposed between the grids, the other two loops being anode-to-anode loops extending in opposite direction and disposed between the anodes, said anode-to-anode loops enclosing the aforesaid grid-to-grid loops, the outwardly oppositely projecting lead-ins of the cathodes having concentric chokes thereon at a suitable point defining proper inductance which forms a resonance circuit with the aforesaid cathode-to-cathode capacitance, the aforesaid glass envelope enclosing the aforesaid loops, chokes and the electrode assemblies.

10. An ultrahigh frequency oscillator tube comprising a glass envelope carrying a pair of electrode assemblies and resonant loops, each of said assemblies including a cathode, a cathode lead-in extending horizontally outward from said cathode, a grid surrounding said cathode, and an anode surrounding said grid, said electrode assemblies being disposed end-to-end on a common horizontal axis, one of the aforesaid loops being a grid-to-grid loop, another loop being an anode-to-anode loop, said loops extending horizontally and said anode-to-anode loop enclosing said grid-to-grid loop, anode lead-ins extending vertically upwardly from the anodes, and a grid loop support extending vertically downward from the nodal point of the grid loop, whereby nearly all of the lead-ins project in different directions at relatively widely spaced points on the glass envelope of the tube.

11. An ultrahigh frequency oscillator tube comprising an evacuated glass envelope carrying a pair of electrode assemblies and resonant loops, each of said assemblies including a generally cylindrical cathode can, a heater filament in said can, a cathode lead-in extending horizontally outward from said can, a grid surrounding said cathode, and an anode surrounding said grid, said electrode assemblies being disposed end-to-end on a common horizontal axis, one of the aforesaid loops being a grid-to-grid loop, another loop being an anode-to-anode loop, said loops extending horizontally and said anode-to-anode loop enclosing the aforesaid grid-to-grid loop, anode lead-ins extending vertically upwardly from the anodes, and a grid loop support extending vertically downward from the end of the grid loop, whereby nearly all of the lead-ins project in different directions at relatively widely spaced points on the glass envelope of the tube.

12. An ultrahigh frequency oscillator tube comprising a glass envelope carrying a pair of electrode assemblies and four resonant loops, each of said assemblies including a cathode, a cathode lead-in extending horizontally outward from said cathode, a grid surrounding said cathode, and an anode surrounding said grid, said electrode assemblies being disposed end-to-end on a common horizontal axis, two of the aforesaid loops being grid-to-grid loops extending horizontally in opposite direction, anode lead-ins

projecting vertically upwardly from the anode-to-anode loops at the anodes, and grid loop supports depending vertically downward from the nodal points of the grid loops, whereby nearly all of the lead-ins project in different directions at relatively widely spaced points on the glass envelope of the tube.

13. An ultrahigh frequency oscillator tube comprising an evacuated glass envelope carrying a pair of electrode assemblies and four resonant loops, each of said assemblies including a cylindrical cathode can, a heater filament in said can, a cathode lead-in extending horizontally outward from said can, a grid surrounding said cathode, and an anode surrounding said grid, said electrode assemblies being disposed end-to-end on a common horizontal axis, two of the aforesaid loops being grid-to-grid loops extending in opposite direction, the other two loops being anode-to-anode loops extending in opposite direction, said loops extending horizontally and said anode-to-anode loops enclosing the aforesaid grid-to-grid loops, anode lead-ins projecting vertically upwardly from the anode-to-anode loops at the anodes, and grid loop supports depending vertically downward from the nodal points of the grid loops, whereby nearly all of the lead-ins project in different directions at relatively widely spaced points on the glass envelope of the tube.

14. An ultrahigh frequency oscillator tube comprising a glass envelope carrying a pair of electrode assemblies and four resonant loops, each of said assemblies including a cathode, a cathode lead-in extending horizontally outward from said can, a grid surrounding said cathode, and an anode surrounding said grid, said electrode assemblies being disposed end-to-end on a common axis with the closed ends of the cathode assemblies adjacent one another, said ends providing capacitance loading for facilitating tuning of the cathodes, one of the aforesaid loops being a grid-to-grid loop, another loop being an anode-to-anode loop, the outwardly oppositely projecting leads of the cathodes having concentric chokes thereon at a suitable point defining proper inductance forming a resonance circuit with the aforesaid cathode-to-cathode capacitance, anode lead-ins projecting from the anodes in a direction normal to the plane of the loops and cathode lead-ins, and a grid loop support connected to the nodal point of the grid loop.

15. An ultrahigh frequency oscillator tube comprising a glass envelope carrying a pair of electrode assemblies and resonant loops, each of said assemblies including a generally cylindrical cathode can closed at its inner end, a tubular cathode lead-in extending horizontally outward from said can, a grid surrounding said cathode, and an anode surrounding said grid, said electrode assemblies being disposed end-to-end on a common axis with the closed ends of the cathode assemblies adjacent one another, said ends providing capacitance loading for facilitating tuning of the cathodes, one of the aforesaid loops being a grid-to-grid loop, another loop being an anode-to-anode loop, the outwardly oppositely projecting leads of the cathodes having concentric chokes thereon at a suitable point defining proper inductance forming a resonance circuit with the aforesaid cathode-to-cathode capacitance, anode lead-ins projecting from the anodes in a direction normal to the plane of the loops and cathode lead-ins, and a grid loop support connected to the nodal point of the grid loop.

16. An ultrahigh frequency oscillator tube com-

prising a glass envelope carrying a pair of electrode assemblies and four resonant loops, each of said assemblies including a cylindrical cathode can closed at its inner end, a heater filament in said can, a cathode lead-in extending horizontally outward from said can, a grid surrounding said cathode, and an anode surrounding said grid, said electrode assemblies being disposed end-to-end on a common axis with the closed ends of the cathode assemblies adjacent one another, said ends providing capacitance loading for facilitating tuning of the cathodes, one of the aforesaid loops being a grid-to-grid loop, another loop being an anode-to-anode loop, said anode-to-anode loop enclosing the aforesaid grid-to-grid loop, the outwardly oppositely projecting leads of the cathodes having concentric chokes thereon at a suitable point defining proper inductance forming a resonance circuit with the aforesaid cathode-to-cathode capacitance, the aforesaid glass envelope enclosing the aforesaid loops, chokes and the electrode assemblies, anode lead-ins projecting from the anodes in a direction normal to the plane of the loops and cathode lead-ins, and a grid loop support connected to the nodal point of the grid loop.

17. An ultrahigh frequency oscillator tube comprising a glass envelope carrying a pair of electrode assemblies and four resonant loops, each of said assemblies including a cylindrical cathode can closed at its inner end, a cathode lead-in extending horizontally outward from said can, a grid surrounding said cathode, and an anode surrounding said grid, said electrode assemblies being disposed end-to-end on a common axis with the closed ends of the cathode assemblies adjacent one another, said ends providing capacitance loading for facilitating tuning of the cathodes, two of the aforesaid loops being grid-to-grid loops extending in opposite directions, the other two loops being anode-to-anode loops extending in opposite directions, the outwardly oppositely projecting leads of the cathodes having concentric chokes thereon at a suitable point defining proper inductance forming a resonance circuit with the aforesaid cathode-to-cathode capacitance, anode lead-ins projecting from the anodes in a direction normal to the plane of the loops and cathode lead-ins, and grid loop supports projecting from the nodal points of the grid loops in a direction opposite that of the anode lead-ins, whereby nearly all of the lead-ins project in different directions at relatively widely spaced points on the glass envelope of the tube.

18. An ultrahigh frequency oscillator tube comprising a glass envelope carrying a pair of electrode assemblies and four resonant loops, each of said assemblies including a generally cylindrical cathode can closed at its inner end, a heater filament in said can, a tubular cathode lead-in extending horizontally outward from said can, a heater lead-in running coaxially through the tubular cathode lead-in, a grid surrounding said cathode, and an anode surrounding said grid, said electrode assemblies being disposed end-to-end on a common axis with the closed ends of the cathode assemblies adjacent one another, said ends forming a radio-frequency condenser represent-

ing a capacitance loading for facilitating tuning of the cathodes, two of the aforesaid loops being grid-to-grid loops extending in opposite directions, the other two loops being anode-to-anode loops extending in opposite directions, said anode-to-anode loops enclosing the aforesaid grid-to-grid loops, the outwardly oppositely projecting leads of the cathodes having concentric chokes thereon at a suitable point defining proper inductance forming a resonance circuit with the aforesaid cathode-to-cathode capacitance, anode lead-ins projecting from the anodes in direction normal to the plane of the loops and cathode lead-ins, and grid loops supports projecting from the nodal points of the grid loops in a direction opposite that of the anode lead-ins, whereby nearly all of the lead-ins project in different directions at relatively widely spaced points on the glass envelope of the tube.

19. An ultrahigh frequency oscillator tube comprising an evacuated glass envelope carrying a pair of electrode assemblies and four resonant loops, each of said assemblies including a generally cylindrical cathode can closed at its inner end, a tubular cathode lead-in extending horizontally outward from said can, a grid surrounding said cathode, and an anode surrounding said grid, said electrode assemblies being disposed end-to-end on a common axis with the closed ends of the cathode assemblies adjacent one another, said ends providing capacitance loading for facilitating the tuning of the cathodes, two of the aforesaid loops being grid-to-grid loops extending in opposite directions, the other two loops being anode-to-anode loops extending in opposite directions, said anode-to-anode loops enclosing the aforesaid grid-to-grid loops, the outwardly oppositely projecting leads of the cathodes having concentric chokes thereon at a suitable point defining proper inductance forming a resonance circuit with the aforesaid cathode-to-cathode capacitance, the aforesaid glass envelope enclosing the aforesaid loops and chokes as well as the electrode assemblies, anode lead-ins projecting from the anodes in direction normal to the plane of the loops and cathode lead-ins, and grid loop supports projecting from the nodal points of the grid loops in a direction opposite that of the anode lead-ins, whereby nearly all of the lead-ins project in different directions at relatively widely spaced points on the glass envelope of the tube.
